UNITED STATES PATENT OFFICE.

EDWIN L. WHITE, OF BROOKLYN, NEW YORK.

DESIGN FOR A HANGER FOR LIGHT-TRANSMITTING BOWLS.

51,517.

Specification for Design.

Patented Nov. 20, 1917.

Application filed September 11, 1917. Serial No. 190,852. Term of patent 7 years.

To all whom it may concern:

Be it known that I, EDWIN L. WHITE, a citizen of the United States, residing at the borough of Brooklyn, county of Kings, city and State of New York, have invented a new, original, and ornamental Design for a Hanger for Light-Transmitting Bowls, of which the following is a specification, reference being had to the accompanying drawing, forming part thereof, in which—

Figure 1 is a side view of a hanger for light transmitting bowls showing my new design, and

Fig. 2 is a front view in a more upright position to better illustrate the front ornamentation.

I claim:

The ornamental design for a hanger for light transmitting bowls, as shown.

EDWIN L. WHITE.
